ATTORNEY

UNITED STATES PATENT OFFICE.

CHARLES O. WYMAN, OF ANOKA, MINNESOTA.

RUNNING GEAR.

1,425,734.

Specification of Letters Patent. Patented Aug. 15, 1922.

Application filed March 23, 1921. Serial No. 454,985.

To all whom it may concern:

Be it known that I, CHARLES O. WYMAN, a citizen of the United States, and resident of the city of Anoka, in the county of Anoka 5 and State of Minnesota, have invented certain new and useful Improvements in Running Gears, of which the following is a specification.

My invention consists of a novel and useful improvement in running gears for automobiles, power trucks, and tractors, where the power is located on the machine and applied to the four carrying wheels for propelling the machine. My invention relates 10

more particularly to that type of machine in which the carrying axles are bent down in the center so as to permit of the motor being located lower on the truck than is usual in the four wheel drive automobile. 15 Further it allows easy access to the driving shafts or driving axles. The front and rear sections can be removed by taking a split key from the ends of the reach and the sections slipped away.

Also to the particular form of reach, which is bent down in different places to allow the motor being located lower than is usual in this style of machine and for other purposes. Further, its being pivoted to the front and 20 rear sections, forming a perfectly flexible frame. Further in the improved steering-knuckle, which excludes all dirt and holds all oil within it, in fact packing the working parts in oil, being ball mounted, so that 25 its operation is easy and strongly and neatly built, and all parts easy of access.

The machine consists of four carrying wheels on which is mounted a power plant, supported by a frame connecting the wheels, 30 in connection with mechanism for transmitting the power properly to the four carrying wheels, to propel the machine.

I use various devices to accomplish this purpose, the construction of some are slightly 35 different, but all embodying the same general principles, enough of which are illustrated in the drawing and described in the specifications to enable those skilled in the art to construct the same; while I have pointed out in the claims the full scope of my invention, in the accompanying drawings forming a part of this specification.

Fig. 1 is a plan view of one of the forms used in my running gear. In this construction by removing split key from ends of the

reach, the front and rear sections can be slipped away without tearing the machine to pieces.

Fig. 2 is sectional view of reach used in my running gear. In this the reach is bent 60 down in different places to permit of the motor being located low down on the machine and for other purposes.

Fig. 3 is cross sectional view of improved axle used in my running gear. In this construction the axle is bent down to permit of motor being located low on the machine, also to give access to the short driving axle. 65

Fig. 4 shows driving connection from triple differential to the four carrying wheels 70 by four independent driving shafts.

Fig. 5 is elevation, showing my enclosed steering-knuckle.

Fig. 6 is cross sectional view of my enclosed steering-knuckle. 75

Fig. 7 shows driving connection direct to jack-shaft or axle.

In the drawings 1 and 1^a represent respectively the forward and rear platforms of my running gear, having axles 2 and 2^a, 80 with their heels 3 and 3^a, which are mounted on axles with knuckles 4 and 4^a, which permits of the oscillating of the wheels for steering the machine.

Platforms 1 and 1^a are joined by a crooked 85 reach 5 which has extended pivots 6 and 6^a, which fit loosely into sockets 7 and 7^a located on platforms, forming a flexible joint and capable of oscillation.

Reach 5 has driving shafts 8 and 8^a 90 mounted on it by bearings 9 and 9^a; shafts extend from differential case 10 to gear cases 11 and 11^a, which are mounted on jack shafts 12 and 12^a. Jack shafts 12 and 12^a are drivingly connected by sprocket chains 13 and 95 13^a, or any desired connection, to driving axles 14 and 14^a.

As power is applied from motor it is transmitted through differential to the four carrying wheels to drive the machine. 100

Fig. 4 shows another mode of driving machine. In this construction I locate triple differential 10 in the center of the machine and drive to each carrying wheel with separate driving shafts. Quadruple shafts 105 8^b e^c d^e, are provided with universal couplings at their respective ends and a spline joint at their center transmitting power from differential 10 to bevel gears located in gear cases 11^b e^c d^e, mounted on the respective 110

- ends of the bent axles, thence by short driving axles 14, 14^a ^b ^c, through the steering-knuckle to the carrying wheels for propelling the machine.
- 5 In Figure 6, 15 shows upper half of casing and 16 shows lower half of the same, which are held together by bolts.
- 17 and 17^a, are screw caps; 18 is sleeve or pivoted stub carrying axle on which wheel hub 19 is mounted; 20 is pivoted driving stub axle or spindle, which is rigidly attached to outer end of carrying wheel hub by linch-pin 21. The spindle passes loosely through sleeve 18.
- 15 On the sleeve 18 there is mounted the carrying wheel hub 19, which is provided with roller bearings and rolls loosely around sleeve. Spindle 20 is flexibly joined to driving axle 14 by universal coupling 22. Sleeve 20 is rigidly joined to or forms a part of internal casing 23, which is provided with pivots 24 and 24^a. Internal casing 23 is loosely mounted within the external casing 4, formed by sections 15 and 16, so as to be oscillated in steering to guide the machine.
- 20 Sections 15 and 16 are rigidly united by bolts clasping the end of the bent axle 2 and forming the external casing 4 which is loosely mounted over the casing 23, acting as a pivot and housing for the same.
- 25 External casing 4 is provided with an oblong orifice 25 on its wheelward side, sufficient for the oscillation of sleeve 18 in turning the carrying wheels to guide the machine.
- 30 A steering arm 26 is rigidly mounted on pivot 24^a which extends through orifice 27. Orifice 27 has sufficient width to allow clearance of arm 26 in its oscillations while operating internal casing 23 with its attachments to guide or steer the machine.
- 35 The casings are provided with ball bearings sufficient to sustain the load carried on the machine and relieve it of the side rack.
- 40 Internal casing 23 is provided with an orifice 28 on its truckward side of sufficient

dimensions to allow of the oscillation of the case in turning to guide the machine.

The chamber in casing 23 forms a housing for universal coupling 22.

50 The steering-knuckle is oiled by removing the screwcap 17 from the upper pivot socket in the casing 4. Casing 23 is bolted to the bottom of the section 16 rendering it easy to mount or dismount the steering arm 26.

55 It is thought that the use and operation of the invention will be thoroughly understood by those skilled in the art.

Various changes in the form proportions and minor details of my invention may be 60 resorted to without departing from the spirit and scope thereof. Hence I consider myself entitled to all such variations as may lie within the intent of my claims.

65 I claim as my invention:

1. In a vehicle running gear of the automobile type, a carrying axle bent down in its center with a framed platform mounted on its respective ends, in combination with a reach crooked down under said platform and 70 pivotally mounted on the same.

2. In a vehicle running gear of the automobile type, front and rear truck sections, consisting of platforms mounted on bent-down axles, in combination with a crooked 75 reach pivotally connected to said platforms, means of transmitting power from the motor to the four carrying wheels.

3. In an automobile running gear of the four wheel drive and steer type, a sub frame, 80 consisting of platforms mounted on axles bent-down at the center with tubular ends through which loosely pass, driving axles flexibly connected to carrying wheels to propel the same, said platforms being pivotally 85 connected to a crooked reach, and a motor located on the machine and drivingly connected with said driving axles.

CHARLES O. WYMAN.
